UNITED STATES PATENT OFFICE.

CHARLES VOLNEY KERR, OF WELLSVILLE, NEW YORK.

CONDENSER.

1,158,231.

Specification of Letters Patent. Patented Oct. 26, 1915.

Application filed October 9, 1913. Serial No. 794,267.

To all whom it may concern:

Be it known that I, CHARLES V. KERR, a citizen of the United States, residing at Wellsville, in the county of Allegany and State of New York, have invented certain new and useful Improvements in Condensers, of which the following is a specification.

My invention relates to steam condensers, and more especially to that class of the jet type and particularly adapted to be used in connection with steam turbine plants.

The objects of my invention are: First; to construct and arrange the different co-operating parts of the apparatus so that the exhaust steam enters the volute condenser casing at a high velocity in a spiral path, thereby creating a cyclonic action in the condensing casing to finely divide the condensing water within the casing and enable the same to thoroughly commingle with the steam and efficiently condense the same. Second; to construct and arrange the parts in order that the water may be sub-divided into a great number of finely divided downwardly moving jets of water which are encountered by a body of rapidly moving exhaust steam deflected upwardly in a spiral path, so that the steam entering the condenser casing not only acts to finely subdivide the water but also has a tendency to sustain or suspend the water in the condenser casing, thereby effecting the maximum utilization of the cooling power for a given quantity of water before said water flows to the collecting chamber and discharge. Third; to arrange the parts of the condenser so that the air liberated from the exhaust steam is readily separated or collected in the condenser and disposed in the path of the water to be easily and efficiently entrained by the said water on its discharge from the condenser, without in any way disturbing the efficient operation of condensing operations. Fourth; to so construct and arrange the parts as to produce a condenser which is most efficient, inexpensive, compact, has few parts, is easily assembled or may be taken apart, quickly repaired, and has low operating cost. Fifth; other objects and advantages of construction will appear from the detailed description to be hereinafter given in connection with the preferred form shown in the drawings.

My invention consists of structural features and relative arrangements of the elements comprising the invention which will

be hereinafter more fully described and particularly pointed out in the appended claims.

In the drawings in which similar reference characters indicate the same parts in the several figures; Figure 1 is a longitudinal central section of the condenser on line I—I of Fig. 2; Fig. 2 is a transverse sectional view on line II—II of Fig. 1; Fig. 3 is a top plan view of the water distributing plate; and Fig. 4 is a development of the spiral ribs on the inner surface of the condenser casing.

Referring to the drawings 1 is the volute condenser casing having connected therewith a collecting chamber 2, provided with a lower opening 3 to which is attached a discharge pipe 4, said pipe 4 having communication with the inlet of any form of centrifugal circulating pump, as shown for example in an application filed by me, Serial No. 803,717.

Within the casing 1 and arranged on the inner surface of the same is a series of spiral ribs or deflectors 5, 5, inclined in an upward direction as shown, and for purposes to be hereinafter described. Attached to the volute casing 1 is a downwardly extending exhaust steam pipe, as shown in dotted lines, which connects with the lateral exhaust inlet 6, said inlet being so arranged and constructed, as shown in Fig. 2, that the steam is made to enter laterally or eccentrically into the chamber of the casing 1 and describe a spiral path and be deflected in an upward direction by impinging against the spiral ribs 5, 5, inside of casing 1. Said casing 1 is provided at its upper side with an opening 7 adapted to receive a water distributor or plate 8 having perforations 9, 95 said plate being provided with a central imperforate dome shaped section 10. Attached to the outside of the casing 1 and over the opening 7 and distributor or plate 8, is a suitably shaped cap 11 having a water inlet 12 at its upper end. Connected with the interior of the dome 10 of the plate 8 is an air pipe 13 which passes through any suitable opening 14 near the top of cap 11, for the purpose of connecting the upper part of the condenser casing 1 and the air collecting dome 10, with the inlet of any suitable air pump, as shown for example in my application Serial No. 803,717, herein referred to.

Centrally disposed within the casing 1 and collecting chamber 2, and having its

lower end securing to the lower part of the collecting chamber 2 and communicating with the inlet of the discharge pipe 4, is a stand pipe 15, provided at the section corresponding with the collecting chamber 2 with a series of holes 16. The upper end of the central stand pipe 15 is arranged within the air collecting dome 10 and is so proportioned and arranged as to leave a clearance 10 between the pipe 15 and base of the dome 10, as shown.

The operation of the invention is as follows:—Water from a circulating pump being admitted by the upper inlet 12 into the hollow cap, it passes through the large number of perforations 9, 9, of the distributor plate 8 and is divided up thereby into a series of vertically disposed jets. The exhaust steam which enters at a high velocity by the lateral disposed inlet 6 effects a cyclonic action within the volute condenser casing 1 and strikes the falling jets of water and dashes them into a fine spray against the spiral ribs 5, 5. As the spiral ribs are inclined upwardly toward the distributor plate 8, the water is held suspended in the casing 1 and against the ribs 5, 5, by said steam, and is thereby prevented from falling too rapidly to the bottom of the collecting chamber 2, so that the downward movement of the water being retarded, the maximum utilization of the cooling or condensing power of a given quantity of water is secured. As the condensed steam and water accumulate in the collecting chamber 2 it passes through the openings 16, 16 of the stand pipe in the form of jets into the interior of said stand pipe 15 and is drawn through the discharge pipe 4 by the suction of a circulating pump, not shown. Any air which has been liberated from the condensed steam and water, and accumulates in the stand pipe 15, is entrained by the water falling through the openings 16 on the same principle as used in hydraulic air compression, and is carried out by the discharge water, thereby insuring a higher vacuum than is produced in the common forms of jet condensers.

50 Any air which is at the top of the condenser casing 1, or stand pipe 15, may accumulate in the dome 10, and then be pumped through the air pipe 13 by any suitable air pump, not shown.

55 It will be seen from the arrangement of the central stand pipe 15 with respect to the overflow from the collecting chamber 2, through the openings 16, and the auxiliary air discharge pipe 13, a higher vacuum than usual can be obtained within the condenser and a better economy in the steam engine or main unit of the plant.

What I claim is:—

1. A jet condenser comprising a volute casing having an upper water inlet and a

lower water outlet, and a lateral exhaust steam inlet interposed between said inlet and outlet and communicating with and adapted to produce a cyclonic action within the casing, and a series of upwardly inclined 70 spiral ribs on the inner surface of the casing corresponding to the steam inlet.

2. A jet condenser comprising a volute casing having an upper water inlet and a lateral exhaust steam inlet below said water 75 inlet and communicating with and adapted to produce a cyclonic action within the casing, a water collecting chamber below and connected with said casing and provided with a discharge opening at its lower end. 80

3. A jet condenser comprising a volute casing having an upper water inlet and a lateral exhaust steam inlet below said water inlet and communicating with and adapted to produce a cyclonic action within the casing, a series of upwardly inclined spiral ribs 85 on the inner surface of the casing, a water collecting chamber below and connected with said casing and provided with a discharge opening at its lower end. 90

4. A jet condenser comprising a volute casing having an upper water inlet and a lateral exhaust steam inlet below said water inlet and communicating with and adapted to produce a cyclonic action within the casing, a water collecting chamber below and connected with said casing and provided with a discharge opening at its lower end, and a vertical stand pipe within said casing 95 and collecting chamber having its upper end 100 communicating with the interior of the casing and its lower end connected with the discharge opening, and provided with means at its lower section to simultaneously drain the water from the collecting chamber and entrain the air in the stand pipe and convey the same to the discharge opening. 105

5. A jet condenser comprising a volute casing having an upper water inlet and a lateral exhaust steam inlet below said water 110 inlet and communicating with and adapted to produce a cyclonic action within the casing, a series of upwardly inclined spiral ribs on the inner surface of the casing, a water collecting chamber below and connected with said casing and provided with a discharge opening at its lower end, and a vertical stand pipe within said casing and collecting chamber having its upper end 115 communicating with the interior of the casing and its lower end connected with the discharge opening and provided with a series of openings at its lower section to simultaneously drain the water from the collecting chamber and entrain the air in the stand pipe and convey the same to the discharge opening. 120

6. A jet condenser comprising a volute casing having an upper water inlet and a lateral exhaust steam inlet below said water 130

- inlet and communicating with and adapted to produce a cyclonic action within the casing, a foraminous water distributing plate inserted in said water inlet, a water collecting chamber below and connected with said casing and provided with a discharge opening at its lower end, a vertical stand pipe within said casing and collecting chamber having its upper end communicating with 5 the interior of the casing and its lower end connected with the discharge opening, said stand pipe having a series of openings at its lower section to simultaneously drain the water from the collecting chamber and 10 entrain the air in the stand pipe and convey the same into the lower discharge opening.
7. A jet condenser comprising a volute casing having an upper water inlet and a lateral exhaust steam inlet below said water inlet 20 and communicating with and adapted to produce a cyclonic action within the casing, a series of upwardly inclined spiral ribs on the inner surface of the casing, a foraminous water distributing plate inserted in said water inlet for sub-dividing said water into a series of vertical jets, a water collecting chamber below and connected with said casing and provided with a discharge opening at its lower end, a vertical 25 stand pipe within said casing and collecting chamber having its upper end communicating with the interior of the casing and its lower end connected with the discharge opening, said stand pipe having a 30 series of openings at its lower section to simultaneously drain the water from the collecting chamber and entrain the air in the stand pipe and convey the same into the lower discharge opening.
- 35 8. A jet condenser comprising a volute casing having an upper water inlet and a lateral exhaust steam inlet below said water inlet and communicating with and adapted to produce a cyclonic action within the casing, a series of upwardly inclined spiral ribs on the inner surface of the casing, a foraminous water distributing plate inserted in said water inlet having a central im- 40
- perforate dome section, a water collecting chamber below and connected with said casing and provided with a discharge opening at its lower end, a vertical stand pipe within said casing and collecting chamber having its upper end under the dome section of the plate and communicating with the interior of the casing and its lower end connected with the discharge opening, said stand pipe having a series of openings at its lower section to simultaneously drain the water from the collecting chamber and 45 entrain the air in the stand pipe and convey the same into the lower discharge opening.
- 50 9. A jet condenser comprising a volute casing having an upper water inlet and a lateral exhaust steam inlet below said water inlet and communicating with and adapted to produce a cyclonic action within the casing, a series of upwardly inclined spiral ribs on the inner surface of the casing, a foraminous water distributing plate inserted in said water inlet having a central im- 55
- perforate dome section, an air pipe connected with the underside of the dome and the outside of the casing to be connected with an air pump, a water collecting chamber below and connected with said casing and provided with a discharge opening at its lower end, a vertical stand pipe within said casing and collecting chamber having its upper end under the dome section of the plate and communicating with the interior of the casing and its lower end connected with the discharge opening, said stand pipe having a series of openings at its lower section to drain simultaneously the water from the collecting chamber and entrain the air in the stand pipe and convey the same into the lower discharge opening.
- 60 75 80 85 90
- In testimony whereof I affix my signature in presence of two witnesses.
